PROCESS OF AND APPARATUS FOR THE
TREATMENT OF MATERIALS SUCH AS
COAL, LIGNITE, ASPHALT, ETC.Randolph J. McRae, New York, N. Y., assignor of
one-half to John W. McKinnon, New York,
N. Y.Application February 28, 1929, Serial No. 343,526
Renewed January 12, 1933

14 Claims. (Cl. 25—75)

My invention relates to methods and processes of treating various materials such as above mentioned, and to apparatus for carrying out said processes, for the purpose of modifying said 5 materials and producing different forms of material from the same, all as hereinafter more particularly set forth. Further objects and advantages of the invention will be in part set forth in the following specification, and in part 10 will be obvious therefrom without being specifically pointed out, the same being realized and attained by means of the methods, instrumentalities and combinations pointed out in the claims hereof.

15 One of the principal objects of my invention, which may serve as a general suggestive illustration as to the nature and scope of the same, is the treatment of coal waste, sometimes called slack, which consists of more or less finely 20 broken or even pulverized coal, usually mixed with some percentage of dirt or other impurities, and which it is almost impossible to utilize in heat production with any degree of efficiency. In order to utilize such material, it is desirable 25 to consolidate the same into more or less compact masses, either with or without the admixture of other combustible materials and with or without the employment of a suitable binder for compacting and holding together the loose material, and many processes and forms of apparatus 30 for treating such material have been suggested and are well known in the art. For various reasons, however, few if any of such methods and apparatuses have achieved the desired degree 35 of efficiency and commercial practicability which has been desired. My invention consists, I believe, in the application of radically new principles to this problem, and employs an apparatus embodying a combination of elements 40 and parts radically different from anything which has been employed in the prior art.

With the above mentioned and other objects of the invention in view, my invention consists in the novel steps and proceedings in treating 45 such material and the novel construction, arrangement and combination of various devices, elements and parts, as set forth in the claims hereof, one embodiment of the same being illustrated in the accompanying drawings and described in this specification.

In the accompanying drawings,

Fig. 1 is a transverse vertical section of an apparatus embodying my invention and designed 55 to carry out my improved process;

Fig. 2 is a horizontal section of the same; and

Fig. 3 is a fragmentary view showing in perspective a detail of the apparatus which will be hereinafter fully described.

In carrying my invention into effect in the embodiment thereof which has been selected for description in this specification and illustration in the accompanying drawings, and referring particularly to Figs. 1 and 2, which illustrate the apparatus which I have devised for the purpose of carrying my improved process into effect, I provide an internally heated cylinder 11, supported rotatably on trunnions 12 and adapted to be rotated in a counterclockwise direction by a pinion gear 13 which engages with a gear 14 fixed on the periphery of the cylinder 11. An idler cylinder 15 is supported rotatably by a shaft 16 journaled in bearings 17. A metallic belt 18 passes around the cylinders 11 and 15 75 and travels in the direction indicated by the arrows in Fig. 1 as the cylinders rotate.

The bearings 17 in which the shaft of the cylinder 15 is journaled, are provided with flanges 20 and are slideable upon members 21. 80 I provide rods 22, which are fitted with adjustable guide members 23 and are rigidly connected to the bearings 17. The ends of the rods 22 are screwthreaded, and nuts 24 are provided thereon so as to permit of the adjustment of 85 the guides 23 so as to contact with rocker arms 25. These rocker arms are rigidly connected to a shaft 26, to which are also rigidly secured levers 27. I provide weights 28 which are connected with the levers 27 by rods 29, these 90 weights acting through the levers 27 and rocker arms 25 to exert a pull on the rods 22, thereby tending to move the cylinder 15 and thus keeping up a constant tension on the belt 18.

A framework is provided for supporting the various moving parts above described, as well as other stationary and moving portions to be hereinafter described, the said framework being designated 30.

The belt 18 is provided with a series of interrupted transverse ribs 49, on the side which is nearest to the cylinders 11 and 15. These ribs are best shown in Fig. 1, but are also shown in detail in the fragmentary view Fig. 3, which shows the same in perspective.

The cylinder 11 is provided with a series of peripheral ribs 48, which, in connection with the ribs 49, provide that the belt 18 shall not come into direct contact with the peripheral surface 110 itself of the cylinder 11, but that there shall

always be a slight space between said cylinder and said belt, the object of which will be made clear hereafter. The cylinder 15 may also be provided with ribs 48 similar to those on the cylinder 11, which, although not necessary for the same operative reasons as is the case with the cylinder 11, still provide that the belt 18 does not ride directly upon the periphery of the cylinder.

10 As will be fully explained hereafter when describing the operation of the machine, the material to be operated on is fed on to the inside surface of the belt 18 and spread thereover before reaching the cylinder 11. The mechanism

15 for depositing material and spreading the same into a layer of suitable thickness comprises a conveyor 31 adapted to deliver material upon said belt and an adjustable scraper 72, the operation of which will be well understood.

20 I also provide a hopper 33 adapted to receive material which has been treated while passing between the belt 18 and the cylinder 11, the said material being removed from said cylinder by a scraper 34 supported by a shaft 35. A suitable conveyor carries away the said material from the hopper 33.

25 In order to carry out the operation of treating material as herein described, it is necessary to heat the cylinder 11 to a substantially high degree. This may of course be done in any suitable way and by any structure which will accomplish the purpose, but the devices which I employ in my invention for heating the cylinder are as follows:

30 35 I provide a rigid stationary element of substantially cylindrical external form, situated inside of the cylinder 11 and adapted to guide and distribute the gases of combustion or other heating means which are introduced into the apparatus. This cylindrical element is mounted upon a hollow shaft 38 which extends laterally out beyond the ends of the cylinder 11 and is supported by uprights 70 (see Fig. 2). From said shaft extend radially spokes 41 which support a rim 40.

40 45 I provide fire-brick or other heat-resisting material in connection with a portion of said rim 40, the same being shown at 42. A pipe 43 (see Fig. 2) carries fuel to tuyères 44, where said fuel is mixed with air admitted through perforations 45, and combustion of said commingled gas and air takes place in the space 60, the hot gases of combustion entering space 61 through slots 62. Perforations 46 in the pipe 38 permit the flow 50 55 of air into the interior of the casing 40, and perforations 47 permit the escape of the exhaust gases of combustion into the member 39.

60 65 The movable parts above described are enclosed within a shell or housing of substantially cylindrical form, which is designated 55. This housing is preferably substantially gas-tight, except for necessary openings for the products of combustion and also for the passage of the hollow shaft 38, suitable packing, as 75, being provided wherever necessary. Suitable manholes will also be provided, as 53 and 54, and a slot, as 58, will be required in the practical apparatus for the purpose of introducing the belt 18. Rods, as 59, may be provided for strengthening the 70 75 casing 55 by holding the ends thereof in position, and devices as 57 may be provided to permit of expansion and contraction.

75 The material to be treated is shown in the drawings and designated 80. This is shown as being deposited on the inside of the belt 18 and

as being reduced to a uniform layer by the scraper 72.

80 It will be understood of course that means must be provided for the escape of gases or other volatile matters, either recoverable or waste matters, which may escape from the material during the process of treatment. In the drawings I have shown in Fig. 1 an opening, as 84, which is adapted for this purpose. I have not described any such means in detail, as such are well known in the art and can easily be supplied by persons familiar with the art to which this invention relates.

85 The operation of my invention is as follows: The cylinder 11 having been raised to the proper temperature, as well as the general space within the housing 55, the material to be treated is introduced into the apparatus and placed upon the belt 18 as above explained. The cylinders are rotated during the heating operation, and the interior of the housing 55 is cleared of air by the admission of steam or inert gases. The conveyors for introducing and for removing the material are also operated, during the heating of the apparatus, so that the temperatures of all 90 the moving parts will approximate to the working temperatures. The cylinders are then kept in rotation at the desired speed, preferably at about from three to twelve or more revolutions per hour, depending on the thickness of the layer 95 of material being treated, the temperature, and the character of the product desired. The greater the speed of rotation, the shorter the period during which the material will be subject to heat treatment, and the slower the rotation the longer 100 the period of heat treatment.

105 The material is carried towards the cylinder 11 by the belt, the thickness of the layer depending upon the height of the adjustable scraper 72 above the belt. As the material proceeds between the belt and the cylinder 11, it is subjected to compression and is held firmly against the periphery of the drum by the belt, where it remains in an undisturbed condition and under pressure during a part of the rotation of the 110 cylinder.

115 As the cylinder proceeds in its rotation, the material is gradually subjected to increasing heat until it reaches the tangential point of departure of the belt. The belt now assumes a 120 straight line, as it unwinds from the drum, and substantially all of the material remains on the drum. The material remains on the drum because the belt unwinds away from it, changing 125 from an arc of a circle to a straight line in a direction away from the arc of the treated material, and also because the slope of the ribs 49 on the belt is greater than the slope of the peripheral ribs 38 on the cylinder. Any material, however, which may adhere to the belt, will 130 merely pass over the cylinder 15 and be fed through on the belt for further treatment, being first commingled with fresh material from the hopper 31.

135 140 As the cylinder 11 continues its rotation, the material carried thereby is removed by the scraper 34 and is dropped into the hopper 33 and removed therefrom by the conveyor connected therewith.

145 In treating material containing a low percentage of volatile matter, such as anthracite coal or coke, a hydrocarbon or other binder may be mixed with the material if desired. This binder may be crude oil, treated oil, still bottoms, tar, or other material capable of acting as a binder 150

when so heated in the process. Low volatile solid materials such as coke or anthracite, may be mixed with a higher volatile solid material, such as bituminous or cannel coal, asphalt, &c., and the mixture treated and a solid fuel produced and valuable volatiles recovered.

In a material such as oil shales, the shale is ground to the required degree of fineness, fed into the apparatus, and processed and the volatiles therefrom recovered. The spent shale does not agglomerate, and is normally a waste product. It is desirable therefore to rotate the cylinder 11 at a higher speed and correspondingly reduce the thickness of the material being treated.

The advantages of my invention have been to a considerable extent indicated in what has been above stated with regard to the construction and operation of the apparatus, but other advantages will be obvious to anyone skilled in the art to which this invention relates, and it is unnecessary to discuss the same in detail.

The continued successful and efficient operation of an apparatus such as has been above described, depends in large measure upon the life of the metallic belt. In addition to the strain on the belt caused by the tension of the idler cylinder, an increased tension is caused by the expansion of the material being treated under heat and also by the expansion of the cylinder 11 itself. When the belt reaches the tangential point of contact with the cylinder 11 and first assumes a curved position over the layer of material, the material is comparatively cool and that portion of the cylinder is cooler than in the following zones. As the hottest zones are approached, the cylinder expands proportionately, and each degree of arc is then slightly longer than it was at said tangential point. The result is that the belt, being cooler than the drum, will be subject to increased tension in these hotter zones, and this effect will be also increased by the tendency to expansion of the material being treated. This factor is in itself a favorable one, inasmuch as greater pressure is thereby applied to the material during its melting or softening stage, but on the other hand a belt of unusual characteristics is required to withstand the strains so set up. It has also been found that the cylinder warps and its shape is distorted under heat and other conditions of operation of the apparatus, and the belt must be adapted to conform generally to such distortion.

I have found that the preferable material for the metallic belt is a chrome iron consisting of more than 13% of chromium and less than 87% of iron. The carbon content is preferably low. Such a material has a high tensile strength of the order of 170,000 pounds per square inch, an elastic limit of more than 140,000 pounds per square inch, and a large elongation factor at the break. It is not affected appreciably by heat treatment, does not absorb carbon, and is practically rustless and resistant to corrosion by gases at elevated temperatures. Furthermore, such a chrome iron product has a very high resistance to fatigue and withstands the flexing of the belt. The larger the cylinder, the flatter the arc thereof and the thicker the metallic belt that can be successfully used. Normally, and within certain limits, the thickest possible belt is desirable compatible with the diameter of the cylinders, and I therefore prefer to use cylinders of large diameter and a thick belt in combination

therewith. For example, on a cylinder twelve feet in diameter, a belt made of chrome iron as above described and having a thickness of the order of 20 gauge is appropriate.

I do not limit myself to the particular details of operation and steps of the process above described, nor to the particular details of construction set forth and illustrated, as the same refer to only one embodiment of the invention and it is obviously that the same may be modified, within the scope of the appended claims, without departing from the spirit and scope of the invention. Various matters of detail may be different, as for instance, the ribs upon both the belt and the cylinder 11 may be continuous, or either or both series of said ribs may be interrupted, and many other permissible variations of detail will be obvious to those skilled in the art to which this invention relates.

I wish also to call particular attention to the fact that I have not by any means fully stated all of the purposes to which this invention may be applied, which, it will be obvious to anyone skilled in the art, are exceedingly extensive. I have described merely a few of the more obvious purposes of the invention, for the purpose of explaining the structure of the apparatus and the scope of the treatment given by such apparatus, but I do not wish to be limited to merely the purposes and objects which have been above set forth.

Having thus described my invention, what I claim as new and desire to secure by Letters Patent is as follows:

1. In an apparatus for the thermal treatment of materials, the following elements in combination: A supporting frame; a pair of cylinders rotatably mounted in said frame; a belt passing around said cylinders; heating means located inside of one of said cylinders; means adapted to rotate said cylinders and said belt; and means adapted to feed material between one of said cylinders and said belt and into direct contact with said cylinder.

2. In an apparatus of the kind described, a structure as specified in claim 1, in which the said belt is provided with ribs on its inner surface.

3. In an apparatus of the kind described, a structure as specified in claim 1, in which the said belt is provided with transversely extending ribs on its inner surface.

4. In an apparatus of the kind described, a structure as specified in claim 1, in which the said belt is provided with transversely extending interrupted ribs on its inner surface.

5. In an apparatus of the kind described, a structure as specified in claim 1, in which one of said cylinders is provided with peripheral ribs.

6. In an apparatus of the kind described, a structure as specified in claim 1, in which one of said cylinders is provided with interrupted peripheral ribs.

7. In an apparatus of the kind described, a structure as specified in claim 1, in which said belt is provided with a series of ribs and one of said cylinders is provided with a series of ribs, the ribs of one series being directed substantially at right angles to the direction of the ribs of the other series, and the ribs of one series being interrupted.

8. In an apparatus of the kind described, a structure as specified in claim 1, in which said belt is composed of a material of high tensile

strength, high resistance to heat and corrosion, high resistance to fatigue and to injury caused by the flexing of the belt.

5 9. In an apparatus of the kind described, a structure as specified in claim 1, in which said belt is composed of a material of high tensile strength.

10 10. In an apparatus of the kind described, a structure as specified in claim 1, in which said belt is composed of a material of high resistance to heat and corrosion.

15 11. In an apparatus of the kind described, a structure as specified in claim 1, in which said belt is composed of a material of high resistance to fatigue and to injury caused by the flexing of the belt.

12. In an apparatus of the kind described, a

structure as specified in claim 1, in which said belt is composed of a material consisting of over twelve per cent. of chromium and less than eighty-eight per cent. of iron.

13. In an apparatus of the kind described, a structure as specified in claim 1, in which said belt is composed of a material consisting of over twelve per cent. of chromium and less than eighty-eight per cent. of iron and in which the carbon content is low.

85 14. In an apparatus of the kind described, a structure as specified in claim 1, in which said belt is composed of a material consisting of approximately sixteen per cent. of chromium and the remainder of an alloy of iron and any 90 other suitable material.
